UNITED STATES PATENT OFFICE.

CHARLES F. MURRAY, OF CHICAGO, ILLINOIS, ASSIGNOR TO AMERICAN STEEL FOUNDRIES,
OF NEW YORK, N. Y., A CORPORATION OF NEW JERSEY.

SWING-MOTION CAR-TRUCK.

No. 895,780.

Specification of Letters Patent.

Patented Aug. 11, 1908.

Application filed November 26, 1907. Serial No. 403,943.

To all whom it may concern:

Be it known that I, CHARLES F. MURRAY, a citizen of the United States, residing at Chicago, in the county of Cook and State of Illinois, have invented certain new and useful Improvements in Swing-Motion Car-Trucks, of which the following is a specification.

My invention relates to railway car trucks, but more particularly or specifically to trucks 10 of the type in which the bolster is swingingly supported as by means of links, bails, or the like, whereby the bolsters and car body have a limited sidewise swing or movement and shift laterally of the car when it passes 15 around a curve in the tracks. The advantages of this style of truck and car are so well-known that they need not herein be set forth.

The principal aim and leading object of 20 my present invention is to modify the usual and customary construction so as to facilitate the removal of the bolster and other parts.

Heretofore the bolster has ordinarily been 25 supported directly by the side frames by means of links or the like, while in my improved and novel construction and arrangement of the parts combined bolster supports or spring guides and column guide castings 30 support the bolster by means of bails or equivalent means swingingly hung on or supported by the castings, and the bolster, which has a transverse groove or recess on its under surface at each end, fits over and rests upon 35 the lower portions of the pair of bails of the opposite side frames. Each bolster support casting has one or more column guide ribs or 40 lugs co-acting with its side frame to guide and direct the casting in its vertical adjustments or movements. Each of the castings may have guiding ribs co-acting only with 45 the inner face of the side frame, in which case the bolster and spring opening of the side frame may have straight vertical edges or 50 margins, while, if the castings have ribs co-operating with both the inner and outer faces of the column portions of the side frames, the openings of the latter are made enlarged in 55 their lower portions to permit ready removal of the castings, as is readily understood by those skilled in the art. In either instance the bolster is raised sufficiently to free or unhook it from the bail, whereupon the casting, bail, springs, and afterwards the bolster itself 60 may be easily withdrawn from the frame.

On the accompanying drawings, forming a part of this specification, I have illustrated several embodiments of my invention, and to these drawings attention is directed in connection with the following detailed description. 60

On the drawings—Figure 1 is a side elevation of the central portion of a railway car truck illustrating one embodiment of my invention; Fig. 2 is a central vertical cross-section of the structure shown in Fig. 1, the bolster being shown unsectioned; Fig. 3 is a perspective view of the bolster support casting which has guiding ribs co-operating with the column portions of the side frame; Fig. 4 is a view on a reduced scale of another embodiment of my invention; Fig. 5 is a perspective view of the bolster support casting used in the truck shown in Fig. 4; Fig. 6 is a perspective view of one of the bails and its 70 supporting shaft employed in the truck shown in Fig. 4; Fig. 7 illustrates another embodiment of my invention; Fig. 8 is a perspective view of the bolster-supporting casting used in this embodiment of the invention; Fig. 9 shows a still further modification of the construction; Fig. 10 illustrates the bolster supporting casting with which the truck shown in Fig. 9 is equipped; Fig. 11 is a view similar to Fig. 9 but illustrates 75 a still further modification of the construction; Fig. 12 is a perspective view of the casting used in each side frame for supporting the bolster; and Fig. 13 is a vertical section on line 13—13 of Fig. 11 as viewed in 80 the direction indicated by the arrows. 85

Referring first to Figs. 1, 2 and 3, it will be noticed that the side frame 20 has a central opening 21 for the accommodation of the bolster and springs, its lower portion being 90 enlarged at 22 for a purpose hereinafter indicated. As is customary, a channel spring plank 23, fastened in any approved manner to the two side frames of the truck, connects the two together and holds them in proper 95 position. On the spring plank and in the enlarged portion 22 of the opening are placed the usual coil supporting springs 24, any suitable number of which may be employed. Resting on these springs I provide a combined 100 spring cap and bolster supporting casting 25 which has a substantially horizontal plate portion 26, from the two opposite ends of which extend upwardly the parallel walls 105 27 equipped at their upper ends with sub- 110

stantially semi-cylindrical sockets 28, while the outer face of each of the walls 27 is supplied with a pair of parallel vertical guiding ribs 29 adapted when the casting is in position 5 in the side frame to co-act with the inner and outer faces of the portions 30 of the side frame, which constitute the columns thereof and form the vertical margins or boundaries of the upper restricted or reduced portion of 10 the central opening of the side frame. The enlarged opening 22 is of sufficient depth, as is clearly illustrated on the drawings, to permit the casting 25 to be withdrawn sidewise or laterally of the side frame after the springs 15 have been taken out and the casting lowered into the enlarged part of the opening. Resting in the alined seats or sockets 28 are the oppositely-extended ends or trunnions 31 of a substantially U-shaped bail 32, over the 20 lower horizontal rounded central part 33 of which is adapted to fit the end of a truck bolster 34, equipped at each end on its under surface with a transverse groove or recess 35 adapted to receive a portion of the bail indicated. In other words, the end of the bolster hooks over the lower portion of the bail whereby to give to the bolster a swinging motion for the purpose well understood 25 in this art, and to limit the lengthwise shifting or travel of the bolster I provide the top surface of each end of the same with an up-standing stop 36 braced by one or more brackets 37 and adapted to strike against the upper portion of the side frame to limit 30 and restrict the movement of the bolster.

It will be readily understood that the parts of the truck may be conveniently disassociated and the bolster removed by first lifting the weight from the springs 24 and taking 40 the same out of the side frame, whereupon the casting 25 and the bail supported thereby may be lowered sufficiently to free the bail from the bolster, and upon further lowering of the parts into the enlargement 22 the casting 25 and the bail may be readily withdrawn sidewise from the side frame, as is obvious. The central opening of the side frame being thus freed from the smaller parts permits lengthwise withdrawal of the bolster 50 therethrough.

In the modication illustrated in Figs. 4, 5 and 6, the side frame 38 has a centrally located bolster and spring opening 39 with straight vertical edges 40 forming columns of the side frame, no enlargement of the opening 39 being provided in this instance. As in the embodiment of my invention described above, this side frame is supplied with the usual and ordinary springs 24, upon the top 60 ends of which is seated a bolster supporting casting 41 having a horizontal plate portion 42 and upstanding end walls 43, each of which is supplied on its outer face with a single inner vertical guiding rib 44 adapted to

coöperate with the inner faces of the columns 65 40 to prevent outward movement of the casting and guide its vertical reciprocations. At its upper end each of these walls 43 has a semi-cylindrical socket or seat 45, the outer ends of which are closed by the walls 43, as 70 is clearly indicated in Fig. 5. A cylindrical shaft or rod 46 of the proper length has its ends resting in and supported by a pair of alined seats 45, and the shaft or rod passes through the upper apertured or perforated 75 ends of a swinging bail 47, over the lower horizontal connecting portion of which the end of the bolster 49 is adapted to be hooked, as in the previous instance, so that the two bails on the opposite sides of the truck bear 80 the entire weight of the bolster and the load resting thereon.

It will be apparent that since the weight is taken off of the springs 24 they may be readily removed from the side frame, whereupon the bolster may be easily unhooked from the bails supporting its opposite ends, whereupon the pair of castings 41 of the truck may be taken out inwardly of the side frames, as is obvious, then the bolster may be withdrawn lengthwise through either of the openings 39 of the two side frames.

In the construction illustrated in Figs. 7 and 8 the side frame 38 is like that shown in Fig. 4, and the bolster supporting casting 49 with the single guiding rib 50 at its opposite ends is substantially like the casting 41, except that at the top of each end wall 51 there is provided an inwardly-extended cylindrical boss or stub shaft 52 integral with the end wall and having a hole 53 extended therethrough. On these alined bosses or supports 52 is hung a bail 54 substantially like the bail 47, cotter pins 55 passing through the holes or apertures 53 maintaining the bail in place. In order to mount the bail in position, its parallel legs are bent together somewhat and then spread apart so that the projections 52 fit in the alined eyes or apertures at the upper ends of the bail.

The only difference between the car truck construction shown in Figs. 9 and 10 from that illustrated in Figs. 4, 5 and 6 is that the bail and its supporting shaft are cast integral 115 so as to form a single unitary piece 56 having oppositely-extended rounded terminal portions 57 adapted to be seated and rock in the sockets 45 of the casting 41 illustrated in Fig. 10, which is in all respects like that shown 120 in Fig. 5.

In Figs. 11 and 12 I have shown a construction in which the bolster supporting casting 58 has on the outer face of each of its end walls 59 a single vertical guiding rib 60, 125 the upper ends of the walls being connected by a round shaft or rod 61 integral with the casting 58. On this rod or shaft is adapted

to be hung a bail 62 having hook-shaped ends 63 adapted to be hung on the shaft 61, as is clearly shown in Fig. 11.

The method of removing the parts from the side frame is obvious from the illustration and description given above. It is to be understood, however, that any of the bolster supporting castings illustrated and described may, if desired, have on each end a pair of parallel column guide ribs, in which case it is necessary to employ the casting in connection with an enlarged opening side frame of the general type shown in Fig. 1. Also if desired the casting 25 shown in Fig. 3 may have only one guiding rib on each end, in which instance side frames with apertures having vertical margins, as illustrated in Figs. 4, 7, 9 and 11, may be used in the car truck.

Although I have described with some degree of particularity a variety of embodiments of my invention, it is to be understood that my invention is not limited to the precise structural details of any of these species, since the devices may be modified in minor details without departure from the substance of my invention or the sacrifice of any of its benefits or advantages.

I claim:

1. In a railway car truck, the combination of a side frame, one or more springs, a bolster support resting on said spring or springs and having one or more column guides co-acting with said frame, a bolster, and means supporting said bolster swinging on said bolster support, substantially as described.

2. In a railway car truck, the combination of a side frame, one or more springs, a bolster

support resting on said spring or springs and having one or more column guides co-acting with said side frame, a bolster, and a bail hung on said bolster support which bears the weight of said bolster, substantially as described.

3. In a railway car truck, the combination of a side frame, one or more springs, a bolster support resting on said spring or springs and having one or more column guides co-operating with said side frame, a bolster transversely grooved on its under surface at its end, and a swinging bail bearing the weight of said bolster and hung on said bolster support, a portion of said bail fitting in the groove of said bolster, substantially as described.

4. In a railway car truck, the combination of a side frame having a bolster and spring opening with substantially vertical straight margins constituting column portions of the side frame, one or more springs, a bolster support resting on said spring or springs and having at each end a single guiding rib adapted to co-operate with the inner surface of the adjacent column portion of the side frame, a bolster, and means bearing the weight of said bolster swingingly mounted on said bolster support, substantially as described.

As evidence that I claim the foregoing as my invention, I have signed the same this 23rd day of November, A. D., 1907, in the presence of two witnesses.

CHARLES F. MURRAY.

Witnesses:

FREDERICK C. GOODWIN,
WALTER M. FULLER.
